CUP DISPENSER

James D. Reifsnyder and Albert F. Miller, Flushing, N. Y., assignors to Lily-Tulip Cup Corporation, New York, N. Y., a corporation of Delaware

Application January 30, 1940, Serial No. 316,294

3 Claims.

(Cl. 312—44)

This invention relates to dispensing apparatus and is particularly adapted for use in dispensing articles such as paper cups or the like.

Devices are well known for dispensing flanged paper cups and the like, one at a time, from a stack of the nested articles. While such known devices are satisfactory for manual operation with some types of cups, difficulty has been experienced in providing suitable apparatus for the purpose which will invariably function without fail, to dispense one cup at a time, and only one, and without deforming the cups, or requiring repeated actuation to deliver a single cup. Yet such positive operation is not only desirable to avoid inconvenience to the user and wastage of cups, but is particularly important where the apparatus is to be used for example, in connection with automatic beverage dispensing machines such as coin controlled equipment, so that there will be no danger that the fluid will be spilled or poured to waste due to the jamming of the cups in the dispenser or upon the failure to promptly deliver a cup in proper position to receive the beverage.

The present invention serves to overcome the above indicated difficulties and provides a dependable and positively operating mechanism which is reliable in operation over long periods of use without necessitating repairs or adjustments.

Various further and more specific objects, features and advantages will clearly appear from the detailed description given below, taken in connection with the accompanying drawings which form a part of this specification and illustrate by way of example a preferred form of the invention. The invention consists in such novel features, arrangements and combinations of parts as may be shown and described in connection with the apparatus herein disclosed.

In the drawing,

Fig. 1 is a vertical sectional view of a preferred form of device embodying the invention;

Fig. 2 is a horizontal sectional view taken substantially along the line 2—2 of Fig. 1 and showing the cup dispensing parts in normal position for supporting a stack of cups at times intervening between dispensing operations;

Fig. 3 is a sectional view similar to Fig. 2, but with the upper casing parts removed and showing the cup dispensing elements in positions as occupied during the separation of a cup from the stack;

Figs. 4 and 5 are developed views of certain cam elements of the device;

Fig. 6 is a perspective view of one of said cam elements, and

Fig. 7 is a sectional view taken substantially along the line 7—7 of Fig. 2.

5 Referring to the drawing more specifically, a stack of nested cups to be dispensed is indicated at 10. As indicated, such cups may be stacked in the customary upright position and more or less firmly nested so that the cup flanges as at 11 of succeeding cups are adjacent but usually spaced apart somewhat. While but four of the nested cups are indicated, it will be understood that usually the contents of an entire carton comprising a stack of 100 or more cups, are 15 initially inserted in the device, the stack being normally covered, for example, by a glass tube 12 closed at its upper end and being readily removable and replaceable vertically in a flanged retaining member as at 13 to permit insertion of a fresh 20 stack of cups whenever needed.

The cups as dispensed from the device are allowed to drop out one by one through a bottom outlet 14, from which each cup may be received either on a suitable supporting hook of known 25 form convenient for the user, or the cups may be received in a suitable supporting structure forming a part of automatic dispensing apparatus.

A plurality of cam members as at 15 are provided at spaced points around the periphery of 30 the lowermost cup of the stack for normally supporting the stack and for individually separating the lowermost cup during the dispensing operation. Each of these cam members as shown 35 may be rotatably mounted on vertically extending shafts as at 16, such shafts each having lower bearings as at 17 fitted with suitable bearing bushings as at 17', and upper bearings as at 18 similarly provided with suitable bushings.

40 The cams may be removably secured to these shafts at their proper angular positions as by set screws as at 19. The lower portions of the shafts 16 may be integrally formed with operating pinion gears as at 20 all of which gears 45 may be adapted to engage a single ring gear as at 21 encircling the pinions and rotatably mounted within a lower casing portion 22. The ring gear 21 in turn may be operated by a lever as at 23 extending to the exterior of the device 50 through a suitable slot 24 formed in the side wall of the casing portion 22. Thus by oscillating the lever 23 arcuately in a horizontal plane, the ring gear 21 may be oscillated on its axis concentric with the stack of cups, and as a result, 55 each of the pinion gears 20 and accompanying

cam members 15 will be oscillated arcuately about the axis of the shafts 16 respectively.

The construction of the cam members 15 which embody important features of the invention, will now be described in detail. Each of these members may be formed with a protuberance or lug as at 25 for extending beneath the flange of the lowermost cup of the stack for normally supporting the stack at times intervening between dispensing operations. These lugs should preferably extend radially inwardly of the stack of cups so as to substantially contact the cup walls to firmly hold the stack in position, the upper surfaces of the lugs having sufficient area to form a secure support for the cup flange. Also each of these lugs as shown in Figs. 2, 3 and 6 should preferably extend arcuately around the periphery of the cam member for a considerable distance so that the stack of cups will be securely supported even after the cam members have moved through a substantial angle from their normal positions when at rest. Inasmuch as a full stack of cups has some substantial weight and may be thrust into the device with considerable force when the user is refilling the dispenser, it is important to support the stack in such manner that the rim or flange of the lowermost cup will not become deformed or torn at any time and thus cause the device to fail to invariably dispense the cups individually. Inasmuch as the supporting area of each of the lugs 25 is necessarily quite limited, these purposes are achieved with the present invention by using a considerable number of the rotatable cam members, for example six or more as shown, so that the supporting members will be spaced apart around the cup flange only by 60° or less.

As the device is operated, just as the supporting lugs 25 are about to release the cup flange, cam surfaces as at 26 on each cam member will enter the space between the flanges of the two lowermost cups for separating the same and positively ejecting the lower cup. As shown in Figs. 4 and 6, these cam portions may be wedge-shaped, the forward or entering portion 27 being above and adjacent the releasing portion of the lug 25. It will be noted that the upper active surfaces of the cam portion 26 are horizontal and flat. Thus when the flange of the lower cup is released from the supporting lugs 25, the flange of the next to the lowermost cup will rest upon these flat surfaces, which will thereafter support the remaining stack of cups in fixed position during the remainder of the dispensing operation and without any tendency to crowd the stack upwardly and thereby deforming or crushing the cup rims due to the weight of the stack. In devices of this general type heretofore proposed, the upper surfaces of the cam members were positioned at a substantial angle to the horizontal, with the result that as the cam portion became wedged between two cup flanges, there was a tendency for the next to the lowermost flange to either become crushed or else the whole stack of cups would have to be raised. If there were a large number of cups in the stack, their weight would give the stack sufficient inertia so that upon rapid operation of the device the cam portions would crush or deform the cup rims instead of raising the stack, unless the rims were made relatively rigid. And with the rim of the lowermost cup thus deformed, it would not be supported in the proper position for dependable operation of the dispenser during succeed-

ing actuations. However, with the cam construction here shown, these difficulties are fully avoided.

After the supporting lugs 25 have been released 5 the lowermost cup and the cam portions 26 have positively separated the lowermost cup from the next succeeding cup, the lower cup is then of course free to fall from the outlet 14. Thereupon a reverse movement of the operating member 10 23 will restore the cam members to their original positions and the lower cup flange will fall from the level of the cam surfaces 28, on to the supporting lugs 25 and the device is ready for the next actuation.

15 In addition to the lower casing portion 22, the mechanism may be housed within an upper casing portion 30 which carries the bearings 18 and also serves as a support for the annular member 13 above referred to and which retains the glass tube 12. The casing portions 22 and 30 may as 20 shown be preferably separable along a horizontal plane passing through the region at the lower surfaces of the cam members 15. Thus the gearing and lower bearings of the shafts 16 may be 25 wholly contained within the lower casing portion and the cam members may be applied at their proper angular positions while still exposed for ready access before the upper casing portion 30 is applied. Also this construction permits the relatively expensive gear mechanism to 30 be standardized for use alternatively with the various cam members and upper structural parts adapted for somewhat different sizes of cups.

As shown in Figs. 2 and 7, the upper and lower 35 casing portions 22 and 30 may be removably secured together as by screws 38 surrounded by spacing bushings as at 39.

As shown, the member 13 may be removably 40 secured to the upper casing portion 30 as by screws 31 passing through a flange 32 and into the upper casing portion 30. The flange 32 in addition to serving as a retaining means for the member 13 also serves to cover and protect the upper bearings 18 and gives the upper portion 45 of the device a finished appearance. The member 13 may also be formed with a depending annular flange as at 33, somewhat constricted toward its lower edge for properly directing the stack of cups into the mechanism.

50 The bottom outlet portion 14, similar to the member 13 may be removably secured as by screws 34 in flange 35 to the lower casing portion 22, the flange 35 serving to cover the lower ends of the bearings 17. It will be noted also that the 55 member 14 as shown extends upwardly as at 36 as far as the cam members, and thus guides the cups so that they will fall directly vertically from the cam members. If the lower casing portion 22 and gearing are to be used for different 60 sizes of cups, it will be merely necessary to change the cam members and the members 13 and 14 in order to have all parts which contact with cups of proper size. The inside walls of the member 14 may be formed with relatively shallow vertical grooves as at 37 to eliminate any 65 tendency for the formation of a vacuum in the space above the lowermost cup as it drops out of the device.

70 While the invention has been described in detail with respect to particular preferred examples, it will be understood by those skilled in the art after understanding the invention that various changes and modifications may be made without departing from the spirit and scope of the invention, and it is intended therefore in

the appended claims to cover all such changes and modifications.

What is claimed as new and desired to be secured by Letters Patent is:

1. Apparatus for dispensing flanged paper cups or the like, one at a time, from a stack thereof, comprising a plurality of rotatable cam members mounted on vertical shafts at spaced points around the periphery of the lower portion of the stack, each of said members having means for supporting the stack while separating the lowermost cup, an annular casing for said members, said casing including a separable upper portion and a lower portion, bearing means for said shafts provided in the said upper and lower casing portions, pinions carried on said shafts and a cooperating ring gear within said lower casing portion for simultaneously rotating said cam members, an annular cup outlet member detachably secured to the bottom of said lower casing portion, and an annular frame detachably secured to the top of said upper casing portion for receiving covering means for the stack of cups.

2. Apparatus for dispensing paper cups or the like from a stack thereof, comprising a plurality of rotatable cam members at spaced points around the periphery of the lower portion of the stack, each of said members having means for supporting the stack and for separating the lowermost cup therefrom, gear mechanism including pinions for simultaneously rotating said members, casing structure for supporting and housing the stack and the dispensing mechanism, said casing structure comprising separable portions including first an annular casing portion for said gear mechanism and formed with bearings for

said pinions, a second and generally complementary superimposed casing portion for said cam members and including bearings therefor, the first of said casing portions carrying a separable depending annular outlet portion, and the second of said casing portions carrying a superimposed separable annular inlet portion for guiding the cups into the mechanism, said last two named portions respectively having cup guiding annular flanges extending upwardly and downwardly respectively to points adjacent said cam members.

3. Apparatus for dispensing flanged paper cups or the like, one at a time, from a stack thereof, comprising a plurality of rotatable cam members mounted on vertical shafts at spaced points around the periphery of the lower portion of the stack, each of said members having means for supporting the stack while separating the lowermost cup, an annular casing for said members, said casing including a separable upper portion and a lower portion, said upper casing portion having an upper wall provided with journals for receiving upper ends of said shafts and having a dependent peripheral side wall, said lower casing portion having a lower wall provided with journals for receiving lower ends of said shafts and having a peripheral side wall in cooperative engagement with said upper side wall, pinion gears on said shafts and a ring gear in driving engagement therewith for imparting simultaneous rotary movement to said cams, said ring gear being positioned within said lower casing portion and having operating means secured thereto and passing outwardly through an opening provided in the lower casing portion wall.

CERTIFICATE OF CORRECTION.

Patent No. 2,268,421.

December 30, 1941.

JAMES D. REIFSNYDER, ET AL.

It is hereby certified that error appears in the printed specification of the above numbered patent requiring correction as follows: Page 1, second column, line 34, for "vertically" read --vertically--; page 2, second column, line 4, strike out "been"; and that the said Letters Patent should be read with this correction therein that the same may conform to the record of the case in the Patent Office.

Signed and sealed this 10th day of February, A. D. 1942.

Henry Van Arsdale,

Acting Commissioner of Patents.
